(57) **CLAIM**

The ornamental design for a confectionery product, as shown and described.

DESCRIPTION

FIG. 1 is a front, top, left side perspective view of a confectionery product showing our new design; FIG. 2 is a top view of the design shown in FIG. 1; FIG. 3 is a bottom view of the design shown in FIG. 1; FIG. 4 is a front view of the design shown in FIG. 1; FIG. 5 is a rear view of the design shown in FIG. 1; FIG. 6 is a right side view of the design shown in FIG. 1; and, FIG. 7 is a left side view of the design shown in FIG. 1. The evenly-spaced broken lines in FIGS. 1-7 illustrate portions of the confectionery product that form no part of the claimed design. The dash-dot-dash broken lines in FIGS. 1-5 illustrate the boundary of the claimed design which forms no part thereof.
